WRAPPING MACHINE

Filed Nov. 19, 1925

2 Sheets-Sheet 2

UNITED STATES PATENT OFFICE.

PAUL PIERCE, OF CHICAGO, ILLINOIS.

WRAPPING MACHINE.

Application filed November 19, 1925. Serial No. 69,959.

This invention relates to a wrapping machine and more particularly to an improved adhesive applying means to be used in connection with the wrapping machine for annular articles such as automobile tire casings, coils of wire and the like.

Wrapping machines of this general type are exemplified by United States Letters Patent No. 1,387,016, granted on August 8, 1921, to John Scherner and Edward Hutchens, and it is an object of this invention to provide an improved means for controlling the application of the adhesive to the wrapping material as it is applied to the article to be wrapped.

It is also an important object of this invention to provide a device of the kind described which automatically shuts off the flow of adhesive when the wrapping material breaks or is exhausted.

Other and further important objects of this invention will be apparent from the disclosures in the specification and the accompanying drawings.

This invention—in a preferred form—is illustrated on the drawings and hereinafter more fully described.

On the drawings:

Figure 1 is a fragmentary vertical section with parts removed and parts in elevation illustrating a wrapping machine embodying the principles of this invention.

Figure 2 is an enlarged fragmentary front elevational view illustrating the improved adhesive applying means of this invention.

Figure 3 is a plan view of the adhesive applying means showing a part of the shuttle in section.

Figure 4 is a fragmentary section on the line IV—IV of Figure 3.

Figure 5 is a section on the line V—V of Figure 2 with parts omitted.

As shown on the drawings:

A suitable base frame 1 affords a support for a usual yoke-shaped shuttle frame 2 in which an annular shuttle 3, having a closure gate 4 is rotatably supported. Journalled longitudinally of the base frame 1 is a main drive shaft 5 which carries a large flat-faced grooved pulley 6, the grooved face of which frictionally engages the periphery of the shuttle 3 to rotate the same within the frame 2.

Suitable supporting and driving rollers, one of which is shown at 6 in Figure 1, are provided for rotatably supporting an annu-

lar article such as an automobile tire casing, coil of wire or the like and rotating the same through the eye of the shuttle 3. The interior of said shuttle affords a chamber which is adapted to contain a suitable adhesive, said adhesive being ordinarily introduced thereinto through a suitable filling cup 7 (Figure 1).

Rotatably mounted on the face of the shuttle 3 is a suitable reel or supply of wrapping material 8, a strip of wrapping material from the reel or supply 8 being indicated by the reference numeral 9. Said strip of wrapping material 9 is led from the reel 8 around a tension device 10 through an edge folder 11 and over an adhesive applying device which will be specifically described hereinafter, to the tire or other annular article 12 to which the wrapping material is spirally applied, due to the relative rotation of said annular article and shuttle in planes substantially perpendicular to each other.

The adhesive applying means comprising the present invention embodies a hollow member 13 which is preferably cylindrical and which is engaged at its inner end with a threaded aperture in the face of the shuttle 3 so that it communicates with the adhesive containing chamber in the interior of said shuttle.

To facilitate the flow of adhesive from the interior of the shuttle to the interior of the adhesive applying member 13, the inner end of said member is bevelled as shown at 14. A suitable lock nut 15 is provided for holding said member 13 in proper position relative to the shuttle. The outer end of the member 13 is closed by a threaded plug 16 engaged in a threaded aperture in the end of said member, as clearly shown in Figure 5.

Pivottally mounted on the member 13, between a shoulder formed between the outer end of said member and a collar 17 pinned to said member, is an arm 18 which affords a pivotal support for one end of a roller 19, the other end of said roller 19 being pivotally supported by an arm 20 which rotatably engages the inner end of the member 13 at a point adjacent the face of the shuttle 3.

In order to permit the flow of adhesive from the interior of the member 13 to the exterior thereof for application to the strip of wrapping material, said member 13 is

provided with a restricted aperture 21 (Figures 3 and 4), the outer edge of which opens into a groove formed in the outer face of said member 13 as clearly shown in Figures 4 and 5 at 22. Slidably mounted in said groove 22 is a valve or control member 23 which serves to cut off the flow of adhesive through the aperture 21, under certain conditions to be described hereinafter. Said valve 23 is provided with an integral extension 24 which is secured to a lateral projection 25 on the arm 18 by means of a set screw 26 so that said valve member is moved to open or closed position by the rotation of the arm 18 relative to the member 13. The arm 18 or plate 20 is provided with suitable counterweights 27 and 28 as shown in Figures 3, 4 and 5 for a purpose to be described hereinafter and the counterweight 28 is notched as shown at 29 for engagement with a stop pin 30 secured to the member 13 whereby the movement of the arms 18 and 20 and of the valve member 23 relative to said member 13 is limited. The tension of the strip of wrapping material 9 on the roller 19 when the machine is running is sufficient to keep said roller 19 in the position shown in dotted lines in Figure 4 and to consequently hold the valve member 23 in such position that adhesive is discharged to the surface of the member 13 through the aperture 21 and is consequently properly applied to said strip of wrapping material. It will be appreciated that in case the strip of wrapping material breaks, centrifugal action would ordinarily be sufficient to move said valve member into closed position as shown by the full lines in Figure 4, provided that the counterweights 27 and 28 are properly proportioned to the speed of the particular machine; I have provided additional means to assure such action under all conditions. Said means comprise a leaf spring 31, one end of which is secured to the face of the shuttle 3 as shown at 32 and the other end of which abuts a pin 33 extending inwardly from the roller end of the arm 20. As shown in the drawings, said arm 20 is so counterweighted as to partially balance centrifugal action and close the valve upon breaking or exhaustion of the wrapping material. The closing of the valve is mainly effected by the spring, but it will be understood that the spring 31 might be omitted since with the counterweights 27 and 28 properly proportioned centrifugal action would be sufficient to close the valve and prevent escape of the adhesive through the aperture 21 under all circumstances when the strip breaks or becomes exhausted.

It will be apparent that I have provided an effective control means for an adhesive applying member adapted for use in connection with wrapping machines of this gen-

eral type, said control means being automatically adapted to shut off the supply of adhesive upon breaking or exhaustion of the wrapping material or upon stopping of the machine. The device which I have provided for this purpose is simple and effective and there is little likelihood of the same getting out of order in the normal operation of machines to which it is applied.

I am aware that numerous details of construction may be varied through a wide range without departing from the principles of this invention, and I therefore do not purpose limiting the patent granted hereon, otherwise than necessitated by the prior art.

I claim as my invention:

1. The combination with a wrapping machine including a rotatable shuttle, adhesive applying means on said shuttle, and valve means for rendering said adhesive applying means inoperative when the shuttle is stopped.

2. The combination with a wrapping machine including a shuttle containing a supply of adhesive, of adhesive applying means associated with said shuttle, and means movable relative to the shuttle and to said applying means for controlling the flow of adhesive from said applying means.

3. The combination with a wrapping machine adapted to apply a strip of wrapping material under tension, of adhesive applying means engaging said wrapping material, and a control valve for the adhesive held open by the tension of the strip of wrapping material.

4. The combination with a wrapping machine adapted to apply a strip of wrapping material under tension, of adhesive applying means engaging said wrapping material, and a spring closed control valve on said applying means normally held open by the tension of the strip of wrapping material.

5. The combination with a wrapping machine adapted to apply a strip of wrapping material under tension, of adhesive applying means engaging said wrapping material, and a counterweighted control valve mechanism on said applying means normally held open by the strip of wrapping material.

6. The combination with a wrapping machine including a shuttle and means for applying a fluid adhesive to a strip of wrapping material carried by said shuttle, of means for controlling the flow of said adhesive, said means normally tending to close due to movement of the shuttle and normally held open by the tension of the wrapping material.

7. In a wrapping machine a hollow adhesive-containing shuttle, a hollow adhesive-applying member communicating with the interior of said shuttle and projecting from the face thereof, a valve controlled aperture in the longitudinal face of said member and

means pivoted on said member for operating the valve controlling said aperture.

8. In a wrapping machine adhesive-containing means, adhesive-applying means associated therewith and counterweighted spring-actuated means pivotally mounted on said applying means for controlling the flow of adhesive therethrough.

9. In a wrapping machine adhesive-containing means, adhesive-applying means associated therewith, and counterweighted means mounted on said applying means for controlling the flow of adhesive therethrough.

10. In a wrapping machine adhesive-containing means, adhesive applying means associated therewith, and valve means movably mounted on the outside of said applying means for controlling the flow of adhesive therethrough.

ing means for controlling the flow of adhesive therethrough. 20

11. In a wrapping machine, adhesive-containing means, adhesive-applying means, means pivotally mounted on said adhesive-applying means for controlling the flow of adhesive therethrough, and stop means for 25 limiting the movement of said pivoted control means.

12. In a wrapping machine, adhesive-containing means, grooved adhesive-applying means, and means slidably mounted in the 30 groove in said applying means for controlling the flow of adhesive therethrough.

In testimony whereof I have hereunto subscribed my name.

PAUL PIERCE.
